AIRPLANE BOMB

Stanley H. Emery, Pasadena, Calif.

Application July 12, 1940, Serial No. 345,156

2 Claims. (CL. 89—1.5)

This invention relates to airplane bombs.

The general object of the invention is to provide a novel airplane bomb which explodes a predetermined distance below the releasing airplane.

A more specific object of the invention is to provide a novel airplane time bomb wherein the time of explosion may be controlled from within the releasing airplane.

Another object of the invention is to provide a novel air plane time bomb having improved safety devices included therein.

Another object of the invention is to provide a novel airplane bomb particularly adapted to be released from an airplane in combat against enemy aircraft therebelow.

Other objects and the advantages of this invention will be apparent from the following description taken in connection with the accompanying drawing, wherein:

Fig. 1 is a fragmentary view of an airplane with my improved airplane bomb and time control means therefor mounted thereon;

Fig. 2 is a central sectional view of the bomb, partly in elevation;

Fig. 3 is an enlarged fragmentary sectional view taken on line 3—3, Fig. 2;

Fig. 4 is a fragmentary sectional view taken on line 4—4, Fig. 2;

Fig. 5 is an enlarged fragmentary sectional view taken on line 5—5, Fig. 2; and

Fig. 6 is an enlarged front view of the control means shown in Fig. 1.

Referring to the drawing by reference characters I have shown my invention as embodied in a novel airplane bomb which is indicated generally at 10. As shown in Fig. 1 the bomb 10 may be carried in the bomb rack 11 of a bombing airplane 12. The airplane 12 includes an instrument panel 13 upon which may be mounted the time control device to be later described.

As shown in Fig. 2 the bomb 10 includes a lower hollow cylindrical body portion 14 having explosive material 15 therein and having a detonating member 16, which may include a primer and a booster, in the upper wall 17 thereof. A hollow streamline tail portion 18 is secured to the body portion 14 as by threads 19 and includes external guiding fins 20.

A bracket 21 within the tail portion 18 supports a clockwork mechanism 22. The mechanism 22 includes a central output shaft 23 shown as coaxial with the bomb. At its upper end the shaft 23 extends through an aperture 24 in the end of the tail portion 18 and terminates in a

socket member 25 having a square sectioned bore 26 therein.

A disk 27 is secured to the lower end of the shaft 23. As shown in Fig. 3, the disk 27 is substantially circular but has a removed portion forming an arcuate contour 28 in the periphery thereof.

An arm 29 is pivoted to the shell 18 as at 30 and includes a roller 31 mounted on the end thereof and engaging the periphery of the disk 27.

A hammer member 32 is pivoted to a bracket 33 which is secured to the shell 18. The hammer member 32 includes an extending portion 34 in line with the detonating member 16 and further includes a lug 35 urged into engagement with the arm 29 by a spring 36. The arm 29 thus holds the hammer from striking the detonating member.

The gear train of the clockwork mechanism 22 includes a spur gear 37 which may be engaged by a dog 38 pivoted to the bracket 21. When the bomb 10 is mounted in the rack 11, an extending portion 39 of the rack engages a slidably pin 40 which is mounted in a fixture 41 on the tail portion 18. The pin 40 engages the dog 38 and urges the latter into engagement with the spur gear 37. When the bomb is released (in a manner to be later described) the pin 40 is urged outwardly by a spring 42 thus releasing the dog 38.

A safety pin 43 at one end extends through the tail portion 18 and at the other end is screwed into the wall 17 as at 44. The pin 43 engages the dog 38 and a projection 44' on the arm 29 as shown in Fig. 3 so that these parts are rendered inoperative when the pin 43 is in position.

The position of the disk 27 relative to the arm 29 may be controlled from within the airplane through a time control indicator device 50 mounted upon the instrument panel 13. The device 50 includes a pointer 51 rotatable over a dial 52 including indicia 53 indicating the distance below the releasing airplane that the bomb will explode. The pointer 51 is secured to one end of a flexible shaft 54 the other end of which terminates in a square portion 58 which slidably and removably engages in the bore 26 as shown in Fig. 5. The shaft 54 is encased in a flexible tube 56. The end of the tube 56 includes a collar 57 which is recessed at 55 to fit over a reduced end portion 59 on the socket member 25.

During manufacture the clockwork mechanism 22 is installed in the bomb in wound or loaded condition and is prevented from unwinding by the pin 43 which engages the dog 38, the latter in

turn engaging the gear 37. The pin 43 is left in position during storage.

When the bomb is installed in the rack 11 the portion 39 holds the pin 40 in engagement with the dog 38. The pin 43 may then be removed and thereafter the mechanism is held in locked position through the pin 40. The member 58 is then inserted into the socket 25.

When it is desired to use the bomb, as upon enemy aircraft, the operator determines the distance between his own plane and the aircraft he wishes to destroy. The pointer 51 is then set to the corresponding distance on the dial 52. It will be readily apparent that this controls the position of the disk 27 relative to the arm 29. The bomb is then released from the rack in the usual manner. The portion 55 disengages from the socket 25 allowing the bomb to fall freely. As the bomb is released the pin 40 releases the dog 38 from engagement with the gear 37. This allows the mechanism 22 to rotate the disk 27. When the arcuate portion 28 approaches the roller 31, the arm 29 is allowed to rotate about its pivot thus releasing the hammer member. The extending portion of the hammer strikes the detonating member 16 which causes the bomb to explode.

From the foregoing description it will be apparent that I have invented a novel airplane bomb that is highly effective for its intended purpose.

Having thus described my invention, I claim:

1. In an airplane bomb construction, a support, a bomb on said support, said bomb including a

hollow body having an explosive therein, a detonating member in said body, a firing hammer for said detonating member, a clockwork mechanism having a time setting shaft, a disk on one end of said shaft, said disk being substantially circular and having an arcuate notched portion in the periphery thereof, a pivoted arm on said body, said arm having a roller mounted on the end thereof, said roller engaging the periphery of said disk, a lug on said hammer, said arm engaging said lug to hold said hammer in a safety position when said roller engages said circular portion of said disk but releasing said hammer when said roller engages the notched portion of said disk, said time setting shaft extending beyond said bomb, a flexible shaft removably engaging the outer end of said time setting shaft, and an indicator member associated with the other end of said flexible shaft, the position of said disk relative to said arm being determined by the position of said indicator member.

2. In a bomb, a body including a time controlled detonating device, means to control the operation of the detonating device, said control means including a pivoted dog, a pin slidable on the body and normally disposed in the path of the dog, a second pin slidable on the body in the path of the dog, said second pin protruding from the body and adapted to engage a portion of a bomb rack to normally hold the second pin in dog-engaging position, said first pin being retractable from engagement with the dog.

STANLEY H. EMERY.
